(57) **CLAIM**

The ornamental design for a support base for solar collector assembly, as shown and described.

DESCRIPTION

This application is related to the following US patent application, having the same inventors and the same title, and filed on the same day as this application: application Ser. No. 29/278,260.

The Support Base for Solar Collector Assembly is used to support solar collector assemblies, typically ground-mounted solar collector assemblies.

FIG. 1 is an isometric view of a support base for solar collector assembly, showing our new design;

FIG. 2 is a front elevational view thereof;

FIG. 3 is a right side elevational view thereof, the left side elevational view being identical;

FIG. 4 is a top plan view thereof; and,

FIG. 5 is a bottom plan view thereof.
